[57] CLAIM

The ornamental design for a retainer for retaining boards, as shown and described.

DESCRIPTION

FIG. 1 is a left side view of a retainer for retaining boards showing my new design;

FIG. 2 is a top view thereof;

FIG. 3 is a front view thereof, the rear being a mirror image;

FIG. 4 is a bottom view thereof;

FIG. 5 is a right side view thereof;

FIG. 6 is a sectional view taken in the direction of the arrows on line 6—6 of FIG. 3;

FIG. 7 is a sectional view taken in the direction of the arrows on line 7—7 of FIG. 3;

FIG. 8 is a sectional view taken in the direction of the arrows on line 8—8 of FIG. 3;

FIG. 9 is a front view thereof, the boards being shown in broken lines for illustrative purposes only.
